UNITED STATES PATENT OFFICE.

ARTHUR W. ROBINSON, OF MILWAUKEE, WISCONSIN.

MOUTHPIECE OR DRAG FOR SUCTION-PIPES FOR DREDGES.

SPECIFICATION forming part of Letters Patent No. 657,568, dated September 11, 1900.

Original application filed December 8, 1899, Serial No. 739,619. Divided and this application filed May 7, 1900. Serial No. 15,854. (No model.)

To all whom it may concern:

Be it known that I, ARTHUR W. ROBINSON, a citizen of the Dominion of Canada, and a resident of Milwaukee, in the county of Milwaukee and State of Wisconsin, (having my post-office address at No. 390 La Fayette street,) have invented certain new and useful Improvements in Mouthpieces or Drags for Suction-Pipes for Dredges, of which the following is a specification, reference being had to the accompanying drawings, in which—

Figure 1 illustrates a side elevation of the invention. Fig. 2 illustrates a plan view thereof.

Drags or mouthpieces have ordinarily been rigidly bolted or otherwise attached to the lower end of the suction-pipe. It frequently happens that the cutter or teeth of the drag or some other part thereof catches on rocks, snags, or other obstructions which will not yield, with the result, if the dredge has any considerable headway or there is much sea running, that rupture is inevitable of some part of the suction-pipe or the mouthpiece, or both. It sometimes happens, indeed, that the suction-pipe will be entirely torn away from the dredge or vessel and dropped overboard. In order to avoid this difficulty, I provide a hinged joint at the upper side of the drag proper, whereby it is connected to the end of the pipe, or rather to a casting attached thereto, and the casting and the drag are both provided with flanges, through which relatively-small bolts pass, so that the drag is held in proper position during all strains which will normally come upon it when in use; but in the event of excessive strains—for instance, the drag or its teeth catching under a ledge of rock or against a submerged tree-trunk or other obstruction which refuses to yield or move—the threads of these relatively-small bolts will be stripped, whereupon the drag or mouthpiece will become free to move, oscillating upon its hinge, and will be held to the pipe only by the hinge, and as it shifts its position relative to the pipe by reason of the stripping of the threads of the small bolts its hold upon the obstruction is loosened, and swinging loosely upon its hinge it passes over the obstruction and can be lifted to the deck of the vessel, or at least out of the water, and fresh bolts quickly

substituted for those that have been stripped. Thus in a few minutes the dredge may be at work again in normal condition. In this way serious and expensive accident to the apparatus and also considerable delays in the work are avoided.

In the drawings A illustrates the lower end of the lower section of the suction-pipe. It is usually made of steel. Other material may be employed, however.

B is a casting which I prefer to attach to the lower end of the pipe A by bolts or in any other suitable manner. C is a flange upon this casting.

D D are two upwardly-projecting lugs, preferably cast integral with the casting and on the upper side of the pipe.

E is the mouthpiece or drag. It is preferably provided with cutting-teeth F, which may be of any preferred form, and it has a lever or arm G, whereby a gate H may be opened in the upper rear portion of the mouthpiece to supply flushing-water when necessary, as is well understood.

The drag has a flange I, which coincides with the flange C on the casting B, and J J are the small bolts referred to which pass through holes made in the flanges.

K K are two lugs on the upper side of the drag or mouthpiece which engage with the lugs D on the casting, and L is a bolt which passes through these several lugs, acting as a hinge or pivot.

M is a plate of metal which extends from the flange I, to which it is riveted, as shown, to another flange N, near the mouth of the drag. This plate acts as a shoe upon which the drag rides over the bottom, whereby too-deep penetration of it into the bottom is prevented.

O is a sling-chain which connects by a bail P or otherwise with the lower end of the pipe or with the casting B, as preferred, whereby the pipe and drag may be elevated when desired in a manner well understood.

The operation of the apparatus is obvious from what has already been stated—that is to say, if the drag or its teeth or any part of them should become caught upon or entangled with a weighty obstruction—as, for instance, under a ledge of rock or against the trunk of a

heavy tree or any immovable object—instead of disastrously rupturing or tearing away the suction-pipe or some part of it or destroying the mouthpiece or drag the threads on the small bolts J J will merely strip, thus freeing the drag and permitting it to swing on the strong and heavy hinge on its upper side, by which it will be securely held to the suction-pipe and its loss prevented. All that is then necessary is to hoist the pipe, put in a few more bolts, screw them up, and the drag is returned to its original operative position.

I do not limit myself to the details described and shown above, because it will be obvious to those who are familiar with this art that alterations may be made in such details without departing from the essentials of the invention.

I claim—

1. In a suction-pipe, a drag or mouthpiece hinged at one side to the pipe and held thereto

at the other side by easily-ruptured devices, for the purposes set forth.

2. In a suction-pipe, a drag or mouthpiece connected to the pipe by easily-ruptured devices, and means whereby the drag or mouthpiece can be recovered after said devices have been ruptured, for the purposes set forth.

3. The combination of a suction-pipe, a drag or mouthpiece, a hinge connection between the two at the upper side of the pipe, and means upon the side opposite the hinge whereby the mouthpiece will be held in operative position unless subjected to excessive strains, for the purposes set forth.

Signed at Milwaukee, in the county of Milwaukee and State of Wisconsin, the 30th day of April, A. D. 1900.

ARTHUR W. ROBINSON.
